UNITED STATES PATENT OFFICE.

GRANT WHEAT, OF CORRY, PENNSYLVANIA.

ELECTRIC LAMP.

1,361,557.

Specification of Letters Patent. Patented Dec. 7, 1920.

Application filed January 8, 1917. Serial No. 141,133.

To all whom it may concern:

Be it known that I, GRANT WHEAT, a citizen of the United States, residing at Corry, in the county of Erie and State of Pennsylvania, have invented certain new and useful Improvements in Electric Lamps, of which the following is a specification.

My invention consists of an improved electric lamp and is particularly adapted 10 for miner's use in mines or other places where combustible gases are present.

One object of my invention is to provide a lamp which will include a plurality of electric bulbs and also to provide means whereby any one of said bulbs may be lighted 15 so that if one of the bulbs burn out or is otherwise incapacitated, another of the bulbs may be lighted without opening any part of the lamp casing.

Another object is to include means within 20 the lamp casing which automatically operates, when any of the bulbs are broken, to immediately eject or throw the broken bulb from its electrical contact and thereby prevent 25 sparking which might otherwise result in the explosion of the surrounding gases.

A further object is to so construct my improved lamp casing that it can be readily sealed so that it cannot be opened by an 30 unauthorized person and closed without detection.

Another object is to provide means whereby the lamp may be easily and quickly secured to a hat or cap and which is operative 35 to firmly hold the lamp against accidental displacement.

A still further object is to so construct my improved lamp that it will be of comparatively simple construction and can be manufactured and sold at a reasonably low cost. 40

These objects, and other advantageous ends which will be described hereinafter, I attain in the following manner, reference being had to the accompanying drawings in 45 which—

Figure 1 is a perspective view of my improved lamp and attaching means therefor.

Fig. 2 is a perspective view of my improved lamp with certain of the parts removed. 50

Fig. 3 is a central longitudinal section of my improved lamp.

Fig. 4 is an enlarged fragmentary section showing certain of the elements of my invention. 55

Fig. 5 is a fragmentary sectional plan view taken on the line 5—5 of Fig. 2.

Fig. 6 is a front elevation of my improved attaching means, with the lamp removed therefrom, showing its position when attached to an element which is designed to be secured to a hat or cap. 60

Fig. 7 is a section on the line 7—7 of Fig. 6.

Fig. 8 is a section on the line 8—8 of Fig. 6.

Fig. 9 is a perspective view of my invention as it appears when attached to a hat or cap, and

Fig. 10 is a face view of a conduit-retaining washer which I employ. 70

Referring to the drawings, 1 is a casing preferably made of material which is a non-conductor of electricity, and has a head 2 which is hollow to provide a chamber 3. 75

A stem 4 projects from the head 2 and has a passage 5 extending therethrough and intersecting the chamber 3. This passage is designed to inclose a conduit 6 containing electric wires 7 and 8. The conduit 6 has its inner end 9 projecting for a short distance into the chamber 3, and a washer or ring 10 surrounds said conduit and fits within a recess 10^a in the head 2 and firmly secures the conduit 6 against relative longitudinal movement with respect to the casing 1. 80

The casing 1 has a projection 11 which extends into the chamber 3 and forms a seat or support for two ends 12 and 13 of two 90 contacting plates 14 and 15 respectively. The plates or conductors 14 and 15 have bent portions 16 and 17 which extend downwardly, and these plates are again bent upwardly as shown at 18 and 19 and follow 95 the contour of the chamber 3 as clearly shown in Fig. 2, the portion 19 of the plate 15 being longer than the portion 18 of the plate 14.

The portions 18 and 19 terminate in two 100 contacting fingers 20 and 21 which are oppositely disposed to a switch 22 (see Figs. 2 and 5). The switch 22 is secured to the shank 23 of a manually rotatable disk or knob 24, the latter having ridges on its peripheral surface to facilitate the turning thereof. 105

The switch 22 has a further bearing upon one end of a metallic plate 25, this plate being connected to the wire 8. The wire 7 is connected to a plate 26 which has a bifurcated end 27 made of resilient metal. The bifurcations or arms 28 and 29 of said plate 26 terminate in cupped ends 30 and 31 and 110

are positioned above the ends 12 and 13 of the two contacting plates 14 and 15.

The cupped ends 30 and 31 have holes 32 which extend entirely therethrough from 5 top to bottom, and the ends 12 and 13 each has a recess 33 in its upper surface as clearly shown in Figs. 2 and 4.

A bracket plate 34 has a pointed end 35 which is driven through the inner surface 10 of the head 2. This bracket plate 34 forms a support for two spring arms 36 and 37, each having a V-shaped recess in its outer end as shown at 38. These V-shaped recesses are designed to engage over the 15 pointed upper ends 39 of electric bulbs 40 and 41, said bulbs being of any of the usual types which have metallic jackets 42 which are in electrical connection with the internal filaments or incandescent wires 43, the 20 jackets 42 being insulated at 44 from a central metallic stem or plug 45 which is also in electrical connection with said incandescent wires or filaments 43.

The jackets 42, when the bulbs are in their 25 operative position within my improved lamp, seat upon the cupped ends 28 and 29 of the spring plate 26 and the metallic plugs 45 are held in electrical contact with the recessed portions of the ends 12 and 13 of the 30 plates 14 and 15 through the medium of the resilient arms 36 and 37 which operate to bear downwardly upon the bulbs 40 and 41, it being noted that the strength of the arms 36 and 37 is greater than that of the bifurcated portions 28 and 29 of the plate 26. Hence, when current is passed through the 35 wires 7 and 8, and considering that the switch 22 has been moved into electrical contact with the finger 21, the current will pass 40 through the member 25, thence through the switch 22, finger 21, plate 15, through the filament in the bulb 41, thence through the cupped end 31 of the plate 26, it being noted 45 that the member 25 and plate 26 are in electrical connection with the wires 7 and 8.

If the switch 22 is turned into engagement with the contacting finger 20, the current will pass through the member 25, thence through the finger 20 to the plate 14, thence 50 through the bulb 40 to the portion 28 of the plate 26.

It will thus be seen that when the switch 22 is in contact with the finger 21, the bulb 41 will be lighted and when the switch is 55 turned into contact with the finger 20, the bulb 40 will be lighted. Fig. 2 shows the bulbs removed for sake of clearness and the switch 22 in its neutral position out of contact with both of the fingers 20 and 21.

60 A reflector 46 is mounted within the head 2 and has a flange 47 which fits within an annular groove 48 in said head. The reflector is of the same general shape as the chamber 3, but slightly shallower so as not 65 to interfere with certain of the elements

above mentioned. The reflector has openings 49 and 50 through which the outer ends of the arms 36 and 37 extend so as to engage the bulbs at points outside of the reflector.

Furthermore, the reflector has a hole 51 70 adjacent the bottom thereof to permit the bulbs and the cupped ends of the plate 26 and their co-operative elements to extend therethrough as clearly shown in Figs. 1, 3, and 4.

A gasket 52 surrounds the flanged portion 75 of the reflector and a transparent glass 53 abuts the gaskets and forms a front covering for the lamp. A clamping ring 54 has an inwardly turned flange 55 which holds the glass cover 53 in contact with said gasket 52, said clamping ring at different points throughout its circumference has inwardly projecting pins 56 which are designed to enter and turn within bayonet slots 57 formed 80 in the outer surface of the casing 1 (see Fig. 2) so that the ring 54 may be inserted, and by giving the same a partial turn, will hold the glass cover 53, gasket 52 and reflector 46 to the casing 1.

The clamping ring 54 is provided with a depending integral extension 58 having perforations 59 therein which register with perforations 60 in a depending extension 95 formed on a bracket 61, the latter being secured to the rear of the head 2 of the casing 1. The extensions 58 and 60 can be sealed together by means of a rivet 62 or a rivet 62 may be inserted through each of the perforations in the extensions 58 and 60, 100 only one rivet being illustrated in the drawing. This rivet may be made of soft material such as lead or Babbitt metal so that an attempt to remove the clamping ring 54 would destroy the rivet above mentioned 105 and it could be readily detected if some unauthorized person had attempted to open or remove the glass cover 53.

The bracket 61, after passing upwardly 110 along the back of the head 2, is turned downwardly as shown at 63 and forms a plate having turned lips 64. The plate 63 has an elongated opening 65 therein through which extend hooked flanges 66 and 67 on a relatively slidable plate 68, said plate also having turned lips 69.

A coiled spring 70 has its opposite ends 115 connected to the plate 63 and to the plate 68 and extends through the elongated opening 65 in said plate 63 as clearly shown in Figs. 6 and 7.

The spring 70 serves to move the plates 63 and 68 in one direction in order to move the lips 64 and 69 toward each other for clamping purposes hereinafter described.

A standard or plate 71 is secured to the cap or hat 22, said standard being bent as shown at 73 to slightly space the portion 74 from the hat proper. To attach the lamp to the hat, the lips 69 are placed over one edge 125 130

of the portion 74, and the entire structure is then slid until the lips 64 may be passed over the opposite edge of the portion 74 thus stretching the spring 70 which, when released, will relatively move the plates 63 and 68 so that the lips 64 and 69 clamp the opposite edges of the portions 74 and thereby hold the lamp securely to the hat.

If either of the bulbs 40 or 41 are broken, 10 the portion 28 or 29 will automatically move the bulb out of the contact with the respective plates 14 and 15, thereby immediately breaking the electrical connection with said bulbs, it being noted as above mentioned 15 that the portions 28 and 29 are resilient and that when the arms 36 and 37 are in engagement with the bulbs 40, these portions 28 and 29 are deflected out of their normal position and hence if the bulbs are broken, the 20 arms 36 and 37 will be relieved of their function and consequently move into their normal positions and the portions 28 and 29 of the plate 26 will then return to their normal positions, and in doing so will move the 25 bulbs out of contact with said plates 14 and 15 as above described.

It will thus be understood that when the portions 28 and 29 are in their normal positions, the plugs 45 of the bulbs will be raised 30 out of contact with the ends 12 and 13 of the plates 14 and 15, thus the function of the cupped ends of the portions 28 and 29 is two fold. First, they form conductors of electricity to the lamp jackets 42, and second, 35 they act to move the plugs 45 out of contact with the plates 14 and 15.

The movement of the cupped ends of the portions 28 and 29 serves to eject or throw 40 the broken bulbs from their seats, and hence prevents any sparking due to the burning out of the filament or for any other reason which might occur if the bulbs were allowed 45 to remain in contact with the plates 14 and 15 and the said portions 28 and 29.

In order to prevent the abrupt bending of 45 the conduit 6 at the outer end of the stem 4, I provide a flexible extension or ferrule 75 which abuts against said free end of the stem 4 and to this ferrule I attach a sleeve 76, the 50 outer end of the sleeve being turned inwardly as shown at 77 to indent the ferrule 75 and thereby provide a connection therewith (see Fig. 3).

Adjacent the outer end of the stem 4, I 55 provide pins or lugs 78 which are designed to enter bayonet slots 79 and thereby prevent longitudinal movement of the ferrule with respect to the stem 4 of the casing 1. This construction prevents crystallization of 60 the wires 7 and 8 which otherwise might occur if the conduit 6 bent directly at the free end of the stem 4.

The standard 71 is made of rigid construction and I preferably make the body portion 65 of said standard of sheet metal as shown

at 80, the latter being reinforced by tough cardboard or "paperoid" 81, the edges of the portion 80 being turned to inclose the reinforcement as shown at 82 (see Fig. 8).

It will be noted that the recess 10^a into which the washer 10 fits, extends at an acute angle to the conduit passage. Therefore, any outward pull on the conduit will cause the washer to move within its recess 10^a and thereby closely bind and firmly secure the 75 conduit to the casing. I therefore provide a very simple construction for effectively retaining the conduit within the stem 4 and head 2.

While I have described my invention as 80 taking a particular form, it will be understood that the various parts of my invention may be changed without departing from the spirit thereof, and hence I do not limit myself to the precise construction set forth, but 85 consider that I am at liberty to make such changes and alterations as fairly come within the scope of the appended claims.

Having thus described my invention, what I claim as new and desire to secure by Letters Patent is:

1. A lamp including a casing having a hollow portion, a conductor of electricity mounted within said hollow portion, an electric bulb, a plate secured to the inner surface of said hollow portion, said plate having a resilient projecting arm forming a seat for said electric bulb and normally operative to hold said electric bulb out of contact with said conductor, means operative to hold the bulb in engagement with said conductor 95 against the action of the resilient arm, said arm having a cupped end with a hole extending therethrough and forming a seat for the bulb and permitting a portion thereof to project through the hole into contact with said conductor, substantially as described.

2. A lamp having a hollow head, bulbs mounted in said head, independent conductors of electricity in contact with one terminal of each of said bulbs, a switch movable into contact with either of said conductors, a plate secured to the head and forming a conductor of electricity, said plate having projecting resilient arms for engagement with the respective other terminals of the bulbs, and means for supplying current to said plate and to said switch, said resilient arms being operative, when said bulbs break, 110 to automatically throw them out of electric circuit, substantially as described.

3. A lamp having a hollow head, bulbs mounted in said head, independent conductors of electricity in contact with one terminal of each of said bulbs, a switch mounted within said head and movable into contact with either of said conductors, resilient means for engagement with the other terminal of each of said bulbs, means for sup- 115 120 125 130

- plying current to said resilient means and to said switch, and other resilient means of greater strength than said first resilient means normally operative to hold said bulbs 5 in contact with said independent conductors, said first resilient means being operative when the bulbs are broken to move them out of contact with said independent conductors, substantially as described.
- 10 4. A lamp casing having a hollow head, a metallic plate secured to the inner surface of said head, a plurality of electric bulbs mounted within said head, a plurality of independent conductors, a switch bearing on 15 said plate and movable into engagement with either of said conductors, means providing electrical connection between said conductors and one terminal of each of said bulbs, means for supplying electric current 20 to the other terminals of the electric bulbs, and means for supplying current to said plate whereby the switch when turned in connection with any one of said independent conductors will complete an electric circuit 25 through a respective bulb, substantially as described.
5. A lamp having a hollow casing, a bulb mounted in said casing, a conduit entering the chamber provided by said hollow casing, 30 electric wires housed in said conduit for supplying current to said bulb, and a ring, said casing having a recess greater in width than the thickness of said ring and into which the ring fits edgewise, said conduit passing 35 through said ring whereby a longitudinal movement of said conduit acts to bind it within the casing, substantially as described.
6. A lamp having a hollow head, a bulb mounted in said head, a conduit entering the 40 chamber provided by said hollow head, electric wires housed in said conduit for supplying current to the bulb, a stem intersecting said head and having a passage through which said conduit passes, and a continuous 45 tubular member made of a single piece of flexible material connected to the outer end of the stem, said member forming an additional housing for said conduit and operative to prevent the abrupt bending of said 50 conduit, substantially as described.
7. A lamp including a casing having a hollow portion, a conductor of electricity mounted within said hollow portion, an electric bulb, a plate secured to the casing and including a resilient arm, said arm having a cupped end forming a seat for said electric bulb and normally operative to hold said electric bulb out of contact with said conductor, and means for engaging said bulb 55 to hold it in contact with said conductor against the resilient action of said arm, substantially as described.
8. A lamp including a casing having a hollow head, an electric bulb within said head, a conductor of electricity mounted 60

within the head, a plate secured to the inner surface of the head and including a resilient arm, said arm having a cupped end with a hole therein, said cupped end forming a seat for said electric bulb and normally operative to hold the bulb out of contact with the conductor, means arranged for engagement with said bulb to hold the latter with one of its terminals in engagement with said conductor through the medium of said hole and 70 against the resilient action of the plate, said cupped end of the arm being designed to contact with the other terminal of the bulb, substantially as described.

9. A lamp including a casing having a hollow portion, a conductor of electricity mounted within said hollow portion, an electric bulb, a resilient plate forming a cupped seat in which one end of said electric bulb loosely rests, said plate being normally operative to hold said electric bulb out of contact with said conductor, a resilient arm having a V-shaped recess for straddling the opposite end of said bulb, and said arm being operative to hold the bulb in engagement 85 with said conductor against the resilient action of said plate, substantially as described.

10. A lamp including a casing having a hollow portion, a conductor of electricity mounted within said hollow portion, an electric bulb, a resilient plate forming a seat for said electric bulb and normally operative to hold said electric bulb out of contact with said conductor, a resilient arm having a V-shaped recess for straddling one end of 90 said bulb, and said arm being operative to hold the bulb in engagement with said conductor against the resilient action of said plate, said plate having a cupped end provided with a hole forming a seat for said bulb and permitting a portion thereof to project through the hole into contact with said conductor, substantially as described.

11. A lamp including a casing having a hollow head, a conductor of electricity mounted within said head, an electric bulb, a plate having a resilient portion forming a cupped seat in which one end of the electric bulb loosely rests, said plate being normally operative to hold said electric bulb out of 110 contact with said conductor, said cupped portion of the plate being provided with a hole, said hole permitting a terminal of the bulb to project therethrough into contact with the conductor, said conductor having a recess designed to receive said latter terminal of the bulb, and means for engagement with the bulb to hold said terminal in engagement with the conductor against the resilient action of the plate, substantially as 115 described.

12. A lamp having a hollow head, bulbs mounted in said head, independent conductors of electricity for said bulbs, fingers electrically connected to said independent con- 130

ductors and having raised portions, a switch movably mounted in said head, and means outside of said head operative to move said switch into engagement with the raised portions of either of said fingers whereby the fingers and switch are frictionally bound together, substantially as described.

13. A lamp having a hollow head, bulbs mounted in said head, independent conductors of electricity for said bulbs, fingers connecting said conductors, a switch movable into contact with either of said fingers and between the fingers and the interior of the head whereby the switch is wedged between said fingers and the head, and means on the outside of said casing operative to move said switch, substantially as described.

14. A lamp having a hollow head, a bulb mounted in said head, a conduit entering the chamber provided by said hollow head, electric wires housed in said conduit for supplying current to said bulb, a stem on said head having a passage through which said conduit passes, a flexible ferrule, a sleeve connected to said ferrule, bayonet slots formed in said stem, and means on said sleeve for entering said bayonet slots to detachably secure the ferrule to the stem, said ferrule also forming a housing for said conduit, substantially as described.

15. The combination of a lamp casing, a bracket secured to said lamp casing and having a member secured thereto, turned lips on said member, a second member movable relatively to said first member and having turned lips thereon, a hat, a standard plate on said hat, and a spring for moving said members relatively toward each other to cause said turned lips to engage opposite edges of said standard to secure the lamp to the hat, said turned lips acting to embrace and snugly fit opposite edges of said standard plate, substantially as described.

16. The combination of a lamp casing, a bracket secured to said lamp casing and having a member secured thereto, turned lips on said member, a second member movable relatively to said first member and having turned lips thereon, a hat, a standard plate on said hat, and a spring for moving said members relatively toward each other to cause said turned lips to embrace and snugly fit opposite edges of said standard to secure the lamp to the hat, one of said members having an opening therein providing oppositely disposed edges, the other of said members having hooked flanges for engagement with said oppositely disposed edges to prevent lateral displacement of said members, substantially as described.

17. The combination of a lamp casing having a hollow portion, light producing means mounted in said hollow portion, a bracket secured to said casing and having an extension provided with a perforation, a cover for said hollow portion of the casing, a member for holding said cover in place to prevent access to the interior of said casing, said member having an extension provided with a perforation designed to register with the perforation in said other extension whereby sealing means may be inserted through said perforations, substantially as described.

18. A lamp including a hollow head, an electric bulb mounted in the head, a stem projecting from said head and having a passage communicating with the interior of the head, an electric conduit entering the head through said passage, a continuous tubular ferrule made of flexible material and located at the outer end of the stem, and a sleeve embracing the adjacent ends of said ferrule and stem and securing them together, said ferrule comprising a sleeve having a hole registering with the passage in said stem, substantially as described.

19. A lamp comprising a hollow casing, a stem projecting from the back of said casing, an electric lamp bulb mounted in said casing, electric conductors leading through said stem to said bulb, a ring through which said conductors extend, said casing having a recess formed therein adjacent to the junction of said stem with said casing to receive said ring and hold it at an acute angle to the stem, whereby the engagement of said conductors with said ring will kink the conductors and prevent them from being pulled out of the casing.

20. A lamp comprising a hollow casing, a seat in said casing for an electric light bulb, said seat including a fixed and a movable terminal to engage with the contacts of the bulb, a spring arm on which said movable terminal is supported, said arm tending to move said bulb out of contact with said fixed terminal, and a yielding arm arranged to bear on said bulb and hold it in said seat, whereby upon the breaking of the bulb said spring arm will operate to interrupt the normal engagement of one of said lamp contacts with said fixed terminal.

In testimony whereof I have signed my name to this specification in the presence of two subscribing witnesses.

GRANT WHEAT.
